UNITED STATES PATENT OFFICE.

CHRISTIAN PEDERSEN, OF ST. LOUIS, MISSOURI, ASSIGNOR TO LANDIS MACHINE COMPANY,
OF ST. LOUIS, MISSOURI, A CORPORATION OF MISSOURI.

THREAD-MEASURING MECHANISM FOR SEWING-MACHINES.

No. 898,776.

Specification of Letters Patent.

Patented Sept. 15, 1908.

Application filed December 10, 1907. Serial No. 405,926.

To all whom it may concern:

Be it known that I, CHRISTIAN PEDERSEN, a citizen of the United States, residing at St. Louis, Missouri, have invented a certain new and useful Improvement in Thread-Measuring Mechanism for Sewing-Machines, of which the following is a full, clear, and exact description, such as will enable others skilled in the art to which it appertains to make and use the same, reference being had to the accompanying drawings, forming part of this specification, in which—

Figure 1 is a side elevation partly in section, of a sewing machine provided with a thread-measuring mechanism embodying the features of my invention; Fig. 2 is a detail front elevational view of the take-up arm and its actuating mechanism and also the stop cam which limits the upward movement of said arm; Fig. 3 is an enlarged perspective view of the clamping plates between which the needle thread passes; and Fig. 4 is a detail perspective view of the stop cam which limits the movement of the take-up arm.

This invention relates to sewing machines, and particularly to the thread-measuring mechanisms on wax-thread sewing machines such as are used for sewing leather.

The main object of my invention is to provide a thread-measuring mechanism of simple construction in which the movement of the shuttle is utilized to draw the needle thread from the supply spool, the quantity or amount of thread that is drawn off at each cycle of operations being controlled or governed by the thickness of the stock being operated on.

Referring to the drawings which illustrate the preferred form of my invention, 1 designates a circularly moving shuttle and 2 designates a curved needle arranged above the work-table 3 and adapted to pass downwardly through the stock being operated on to receive the needle thread which it pulls upwardly through the stock to form a loop for the shuttle to pass through so as to lock the needle and shuttle threads together. The needle thread 4 which leads from a supply spool, not shown, passes over idlers 5 and 5^a to a roll on the front end of a take-up arm 6 arranged below the work-table, said take-up arm being loosely mounted on a shaft 7 journaled in a bearing 8. The shaft 7 is rocked by means of a cam-actuated lever 9 that is

connected to an arm 10 on said shaft, and 55 said shaft is provided with a second arm 11 having a portion that is arranged in alignment with the take-up arm 6 so as to depress it to set the stitch when the shaft 7 is rocked in one direction. The needle thread 4 passes 60 between a pair of plates 12 and 13, and means is provided for forcing these plates together to lock the thread and prevent it from being drawn off the supply spool. The means herein shown for actuating the clamping plates consists of an elbow-shaped lever 14 provided on its vertically disposed arm with a roller 15 that travels on the periphery of the cam block 16 which actuates the lever 9, and on the horizontally disposed arm of said 70 elbow lever 15 is an adjustable device 17 that bears upon the top clamping plate 13. The clamping plate 13 is preferably formed of spring material, and is connected at one end by means of fastening devices 13^a to the underneath rigid clamping plate 12.

The periphery of the cam block 16 has a cut-out portion 16^a and when the roll on the vertical arm of the elbow lever 14 is traveling in said cut-out portion the device 17 in the 80 horizontal arm of said lever will not exert sufficient pressure on the plate 13 to lock or clamp the needle thread.

The presser-foot consists of a pivotally mounted lever 18, the inner end of which 85 bears upon the stock A and clamps it down upon the work-table and the rear end of said lever is connected to a link 19 that is fastened to an arm 20 on a rock shaft 21 provided with a cam 22 that is arranged in 90 alignment with the take-up arm 6 so as to control and limit its upward movement. As this stop cam 22 is moved by the presser-foot 18 it is obvious that the position of said cam will vary according to the thickness of 95 the stock, and as said cam limits the upward movement of the take-up arm, the time at which said take-up arm comes to rest in its upward movement will vary.

During the time the needle is moving upwardly through the stock to form a loop in the needle thread 4, said thread will be locked or clamped by the plate 13 so that no thread can be drawn off the supply spool, the slack in the thread between the clamping 105 plates and the stock being taken up by the take-up arm 6. After a loop has been formed in the needle thread and the point of the

shuttle has passed through said loop the cut-out portion 16^a in the periphery of the cam block 16 comes into alignment with the roll on the vertical arm of the elbow lever 14, 5 thus permitting said lever to move slightly and remove the pressure from the plate 13 so as to release the needle thread. No thread is drawn off the supply spool, however, until after the take-up arm has come into contact 10 with the stop cam 22, due to the fact that the spring plate 13 exerts sufficient tension on the plate to prevent it from being drawn off the supply spool until it is subjected to a strong pull or jerk. The upward movement 15 of the needle and also the movement of the shuttle when it first enters the loop in the thread pulls the take-up arm 6 upwardly and while said take-up arm is moving upwardly no thread will be drawn from the supply spool. As soon as the take-up arm comes 20 into engagement with the stop cam 22, however, all the slack in the thread will have been taken up and the movement of the shuttle will pull a quantity of thread from the supply spool. The amount of thread 25 that is drawn off the supply spool at each cycle of operations will vary according to the thickness of the stock, due to the fact that the time at which the take-up arm comes to rest in its 30 upward movement varies according to the position of the stop cam which is controlled by the presser-foot. When very thick stock is being operated on the upward movement of the take-up arm is arrested soon after the 35 point of the shuttle has entered the loop in the thread so that the shuttle will draw more thread from the supply spool than when thin stock is being operated on because the take-up arm is not arrested as soon in its upward 40 movement when thin stock is being operated on as when thick stock is being operated on. With thin stock the shuttle does not commence to draw the thread from the supply spool until some time after it has entered the 45 loop in the thread so that only a small quantity of thread will be drawn off the supply spool. After the shuttle has passed out of the loop in the thread the take-up arm 6 is moved downwardly to draw the threads into 50 the stock and set the stitch. While I have herein shown my invention applied to a sewing machine having a curved needle arranged above the work it will, of course, be understood that my broad idea could be embodied 55 in other types of sewing machines.

I prefer to make the link 19 adjustable so that the length of same can be varied to cause the stop cam 22 to operate at the proper time, and to this end I have provided 60 said link intermediate its ends with a turn buckle 19^a. The stop cam 22 is also made adjustable for a similar purpose, said cam consisting of a plate that is adjustably connected by means of screws to the hub 22^a of 65 the cam.

Having thus described my invention, what I claim as new and desire to secure by Letters Patent is:

1. A sewing machine provided with a thread-measuring mechanism, comprising a shuttle which is adapted to enter a loop in the needle thread, a device for taking up the slack in the thread between the source of supply and the stock being operated on, and means controlled by the presser-foot of the machine for arresting the movement of said take-up device before the shuttle has passed out of the loop in the thread so that the shuttle will draw thread from the supply; substantially as described. 80

2. A sewing machine provided with a thread-measuring mechanism, comprising a shuttle which is adapted to enter a loop in the needle thread, a device for taking up the slack in the thread between the source of supply and the stock being operated on, a member for arresting the movement of the take-up device before the shuttle has passed out of the loop in the thread to cause the shuttle to draw thread from the supply, a presser-foot, and a connection between said member and presser-foot; substantially as described. 85

3. A sewing machine provided with a thread-measuring mechanism which consists of the following elements; a shuttle that is adapted to enter a loop in the needle thread, automatic means for intermittently clamping and releasing the needle thread, a take-up device engaging the thread between the stock being operated on and said clamping means, and means controlled by the presser-foot of the machine for arresting the movement of said take-up device before the shuttle has passed out of the loop in the thread so that said shuttle will pull different quantities of thread off the supply as the stock varies in thickness; substantially as described. 95

4. A sewing machine provided with a thread-measuring mechanism, comprising a shuttle that is adapted to pull thread from the supply, a take-up arm, a cam adapted to engage and limit the upward movement of said arm, a presser-foot, and a connection between said cam and presser-foot; substantially as described. 100

5. A sewing machine provided with a presser-foot, a take-up arm for keeping the needle thread taut, a cam for limiting the movement of said take-up arm in one direction, a presser-foot, a connection between said cam and presser-foot, and a shuttle for pulling thread from the supply after said take-up arm has come to rest; substantially as described. 115

6. A sewing machine provided with a presser-foot lever, a take-up arm for keeping the needle thread taut, a shaft provided with a cam that is arranged in alignment with the take-up arm for limiting its movement in one direction, a connection between said shaft, 120

130

and the rear end of the presser-foot lever, and a shuttle adapted to pull a quantity of thread from the supply after the take-up arm has engaged said cam; substantially as 5 described.

7. A sewing machine provided with a loosely mounted take-up arm for keeping the needle thread taut, an adjustable stop cam for limiting the movement of said take-up 10 arm in one direction, a pivotally mounted presser-foot, a connection between said presser-foot and stop cam, and a shuttle adapted to pull thread from the supply after the stop cam has arrested the movement of 15 the take-up arm; substantially as described.

8. A sewing machine provided with a clamping plate under which the needle thread passes, means for causing said plate to intermittently lock and release the needle thread, 20 a take-up arm for keeping the thread taut, a cam for limiting the movement of said take-up arm in one direction, means controlled by the thickness of the stock being operated on for determining the position of said cam, and 25 a shuttle for drawing thread off the supply after the take-up arm has been arrested by said cam; substantially as described.

9. A sewing machine provided with a yielding plate underneath which the needle 30 thread passes, a lever adapted to engage said

plate, a cam for intermittently actuating said lever to cause said plate to lock said thread, a take-up arm for keeping the thread taut, a device actuated by the presser-foot of the machine for limiting the movement of said 35 take-up arm in one direction, and a shuttle adapted to draw thread from the supply after the take-up arm has been arrested by said device; substantially as described.

10. A sewing machine provided with a tension device through which the needle thread passes, a take-up device for keeping the thread taut between said tension device and the stock being operated on, a needle for forming a loop in the thread, means for locking the thread, a shuttle adapted to enter the loop in the thread, a presser-foot, and means controlled by the presser-foot for arresting the movement of the take-up device before the shuttle has passed out of the loop in the 50 thread so that said shuttle will draw a quantity of thread off the supply; substantially as described.

In testimony whereof I hereunto affix my signature in the presence of two witnesses, 55 this seventh day of December 1907.

CHRISTIAN PEDERSEN.
